BENGT M. W. HANSON, OF HARTFORD, CONNECTICUT; EINAR A. HANSON AND CLARENCE E. WHITNEY, EXECUTORS OF SAID BENGT M. W. HANSON, DECEASED.

GRINDING WHEEL.

Original application filed May 21, 1923, Serial No. 640,351. Divided and this application filed January 22, 1925. Serial No. 4,107.

The present application is a division of my application S. No. 640,351, filed May 21, 1923.

This invention relates to the art of grinding, and has particular reference to improved grinding wheels for use in grinding grooved or threaded members, such as screws, taps or the like, so as to give the grooves or threads accuracy and precision.

10 The aim of the present invention is to provide improved grinding wheels by means of which threaded, serrated or grooved members may be very quickly ground with extreme accuracy in all particulars so that 15 a superior product may be more economically produced.

In accordance with the present invention, the grinding wheel is provided with a plurality of concentric cutting edges or ribs adapted to simultaneously grind or operate upon a plurality of grooves or convolutions, for instance, the convolutions of a thread or threads. By the use of such a wheel, the speed at which the grinding operations are 20 performed is very greatly increased, and the wear upon the serrations is materially decreased so that the time consumed in maintaining the grinding wheel in condition for accurate grinding is considerably reduced 25 and the likelihood of errors in the work, which would be present if a grinding wheel with a single cutting edge were employed, due to the rapid wearing down of that edge, 30 is substantially eliminated.

35 A further object of the invention is to provide an improved grinding wheel, the serrations of which are so arranged or constructed that a cooling fluid may be passed, during the entire grinding operation, 40 through spaces provided between the grinding wheel and each of the ribs or the convolutions of the thread operated upon, so that the work is prevented from becoming overheated and having its temper drawn by 45 the heat generated during the abrasive action. A further advantage of the arrangement of the serrations on the wheel is that the heat of the abrasive action on each convolution or rib on the work, since each convolution at any one instance is operated 50 upon on one side face only, is relatively less than would be the case if both side faces of the convolution were simultaneously op-

erated upon by the serrations. The arrangement of the serrations on the grinding wheel, 55 in addition to providing spaces through which the fluid may pass so as to maintain the work relatively cool during the grinding operation, is also of advantage in that the serrations may be accurately trued, there being ample room between the serrations to 60 accommodate truing mechanism and there being no necessity in shaping the serrations at the roots of the grooves therebetween.

In accordance with one phase of the invention, the grinding edges or ribs on the grinding wheel are so arranged and constructed that they will grind increments from the convolutions of the thread; that is to say, 65 they will grind the thread down to its proper form in stages or steps, each rib or serration performing that portion of the duty assigned to it. It is possible, by employing a stepped serrated wheel of this sort, to accurately true the thread of the work 70 by passing the grinding wheel but once along the work and, since a plurality of grinding edges or ribs are operating simultaneously, the time required to finally grind the thread 75 and take out all of the imperfections and inaccuracies therein, due to hardening or other causes, will be materially reduced, so that the tap or screw can be ground at a less cost. 80

Further objects of the invention will be in part obvious and in part pointed out herein- 85 after more in detail.

The invention will be better understood by reference to the following description in conjunction with the accompanying drawings in which similar reference characters 90 refer to similar parts.

Figure 1 is a plan view showing one form which the grinding wheel may take, and a general arrangement or apparatus for supporting the grinding wheel and work upon 95 which it is to operate;

Fig. 2 is a diagrammatic view showing another form which the wheel may take, and the manner in which it operates upon a threaded member;

Fig. 3 is a diagrammatic view showing the manner in which the serrations of the grinding wheel illustrated in Fig. 1 successively cut small increments from the thread;

Fig. 4 is a similar view showing the manner in which a thread or groove is ground

when the grinding wheel illustrated in Fig. 2 is employed;

Fig. 5 is a view showing the manner in which a Whitworth thread may be ground;

Fig. 6 is a diagrammatic view showing the relative positioning of a grinding wheel and work for grinding threads of large lead;

Fig. 7 is an end view of the arrangement shown in Fig. 6, and additionally indicates the position of the device for truing the grinding wheel; and

Fig. 8 is a detail view showing an arrangement which permits of angular adjustment of the grinding wheel.

The drawings show several forms which my improved grinding wheel may take, it being understood that these showings are merely by way of illustration and not to be construed in any way as limitations of the scope of my invention. Quite obviously, my improved grinding devices, the apparatus and method of truing or shaping the same, and the method of grinding resulting from the use of my improved grinding devices may be employed in or used in combination with machines of appropriate construction or design. The machine shown in the accompanying drawings is illustrated more or less diagrammatically for that reason.

Referring to the drawings and, more particularly, to Fig. 1, there is provided in the apparatus a base 10 upon which is slidably mounted the grinding device, here having the form of a grinding wheel 11, and a carriage 12 having suitable head and tail stocks 13 and 14, respectively, for supporting a piece of work indicated at 15. During the operation of grinding, the wheel 11 is rotated rapidly but has no movement in the direction of its axis. At the same time, the work 15 is slowly rotated, as by means of a splined shaft 46, and is moved axially, as by means of a lead screw 51 associated with the carriage 12 and connected to the shaft 46 by change gears 50. The relative motions in the work are so proportioned that serrations provided on the periphery of the grinding wheel follow the threads of the work 15 to grind out the excess metal therefrom or resurface the same, whereby the threads are cut down accurately to their proper size and form. The wheel 11 is mounted on a shaft 17 journalled as at 18 on a slide 19 which may be moved back and forth in a direction perpendicular to the axis of rotation of the wheel by means of a screw 20 having a hand wheel 21. If desired, the screw 20 may be provided with a micrometer 22 by means of which very fine accurate adjustment of the positioning of the grinding wheel may be made. A pulley 23 may also be provided on the shaft 17 to rotate the grinding wheel very rapidly.

The grinding device 11 is in the form of a cylindrical member formed of abrasive material such as carborundum, and has on its periphery a plurality of serrations or cutting edges. By preference, each of these serrations is in the form of a separate continuous concentric ring or rib to the plane of which the axis of the wheel is perpendicular. One of the generic features of the present invention resides in so arranging or shaping these serrations or cutting edges of the grinding devices (whether said edges are stepped or arranged for increment grinding or not) that a cooling fluid, during the grinding operation, may pass between the grinding wheel and each rib or convolution of the work operated upon so as to minimize the heating effect of the abrasive action on the work and thereby prevent the latter from having its temper drawn. This object may be accomplished by variously arranging or shaping the serrations, as, for example, by making the grooves 27 in the grinding wheel relatively deeper than the actual grinding surfaces of the serrations. The side faces of the serrations may be trued for a distance less than their depths. By preference, the serrations in the grinding wheel may be so arranged that at any given time each of the convolutions of the work is operated upon on one face only; for instance, the serrations or cutting edges of the grinding wheel may be spaced apart a distance further than that between adjacent convolutions so that the serrations will grind non-adjacent convolutions of the thread groove. It is to be understood that the present invention is susceptible of use in grinding grooves and threads of various forms on pieces of work of different kinds, and the machines illustrated in the drawings may be employed for grinding multi-threads as well as single threads. In the drawings, the serrations of the grinding wheels are shown as being spaced apart so that they occur at every other convolution on the thread of the work, it being obvious, however, that they may be otherwise spaced depending upon the character of the work.

By preference, the serrations or cutting edges of the grinding wheel are spaced apart equal to a multiple of the distance between the successive convolutions of the screw operated upon. When a thread of very fine pitch is to be ground, it may be found to be of advantage to space the serrations three or four times the distance between the adjacent convolutions of the thread and the screw. As explained hereinafter more in detail in connection with the description of the truing device, the arrangement of the serrations on the grinding wheel, in addition to providing cooling fluid passages therein, permits ready and accurate truing

of the grinding faces of the serrations, there being ample room between the serrations to insert the diamond points.

In accordance with one phase of the invention, the grinding wheel is arranged so that its serrations will successively grind increments from the successive grooves or convolutions of the work. To this end, the grinding device may have serrations or cutting edges of varying or different sizes or shapes or both, so that, as the grinding wheel is passed longitudinally of the work, each cutting edge or serration will perform but a portion of the grinding operation, the first cutting edge grinding away a small portion or portions from the sides or (and) root of the thread grooves, as the case may be; the second serration taking off a little more, either from the same part, face or portion or portions of the thread convolutions, and on which a previous serration operated, or on a different face or portion thereof, and so on, until the thread groove is of a proper size and shape in cross section. In the illustrated disclosures of the drawings, the grinding wheel serrations are shown as being of successively increasing diameter or height, and at equal distances from the axis of the wheel, as being of successively increasing width so that the successive serrations will progressively grind small increments from the sides and roots of the grooves of the threaded members, but it is to be understood that these showings are by way of exemplification only and, if desired, the construction and arrangement may be such that the successive serrations will grind different portions of each thread convolution or groove, as, for example, one serration may grind one face or portion of the thread groove and the next one will grind the other face or root thereof, and so on. If desired, the serrations may be so arranged that they will progressively grind successive increments from the root of the thread groove or from both the sides and the bottom or root of the groove or portions thereof.

Referring more specifically to the drawings, in Fig. 1 the serrations of the grinding wheel are formed to grind V grooves or threads on the piece of work or tap. These serrations are of progressively increasing size, in the present instance the serrations being all of the same shape and of progressively increasing diameter so that they will progressively grind small portions from the sides and root of the thread groove. It will be seen that the serration 29 is slightly higher, i. e., of greater diameter, than the preceding one 28; the serration 30 is of slightly greater diameter than the one 29, and so on until the final serration is reached (in the present instance the serration 31) which is adapted to give to the thread groove its final shape and size. It will be noted that

these serrations are of progressively increasing width at like distances from the axis of the grinding wheel. During the operation of grinding the work, the latter is rotated and is moved longitudinally so that the serrations of the grinding wheel follow the groove in the work. The serration 28 will grind a small V shaped increment 28' (referring to Fig. 3); the next serration 29 will grind an additional increment 29'; the serration 30 will grind an increment 30'; and, finally, the serration 31 will take an increment 31', thereby finishing the thread to exact size and shape.

The grinding wheel shown in Fig. 2 and designated by the character 11^a is generally similar to the grinding wheel shown in Fig. 1, with the exception that the serrations are truncated. These serrations, designated by the numerals 28^a, 29^a, 30^a and 31^a, are of progressively increasing height and, preferably, their truncated edges are of substantially the same width. The serrations are of similar shape and are shown as being spaced apart so as to operate at any one moment on every other convolution of the thread groove. When this wheel is employed for grinding a grooved or threaded member, the serrations will grind successive increments respectively designated by the characters 28^a', 29^a', 30^a' and 31^a', as shown in Fig. 4.

Fig. 5 diagrammatically illustrates the successive increments which a grinding wheel would take from a piece of work, the grinding wheel having its serrations so formed as to grind a Whitworth thread. The construction of the grinding wheel and its mode of use would be similar to those described in connection with the other two grinding wheels illustrated.

As an instance of one type of truing device which may be employed to advantage for shaping the serrations of the grinding wheels, reference may be had to the arrangement shown in Fig. 1 and which is made the subject matter of a separate application. Each of the grinding wheels may be formed from a generally cylindrical integral member of abrasive material or may constitute a structure built up of abrasive disks, as desired. The shaping and truing of the serrations on the wheel may be done by means of diamond points 35, 36 and 37 mounted on a slide 38 which may be moved back and forth, in parallelism with the axis of the work spindle, on the base 10 by means of a screw 39 having a hand wheel 40 and indexed by a micrometer or scale, as at 41.

The diamond points 35 and 37 may be moved across the respective faces of the serrations, and the diamond point 36 may be advanced by suitable screws provided with hand wheels or handles 42. The extent to which the diamond points may be

1 moved towards the axis of the wheel may be determined by the scales 43. The points 20 35 and 37 are angularly disposed in accordance with the side angles of the thread to 25 be ground, and may be adjustable. By means of the screw 20, the wheel may be brought into position adjacent the diamond points 35, 36 and 37, and thereafter the faces of the serrations are trued to the form 10 and size desired. The diamond point 35 is arranged to cut the right hand side faces of the serrations (Fig. 1), and the diamond point 37 cuts the face on the left hand side of each serration. The diamond point 36 15 may be used to rough out the serrations to the approximate depth and to truncate the serrations.

20 To true the serrations of the grinding wheel shown in Fig. 1, the wheel is first moved by the screw 20 into operative relation to the truing devices; the slide is indexed to bring one of the diamond points, say the one 35, into proper relation to one, 25 of the serrations, for instance the first one 28; and then the diamond point 35 is moved back and forth along the right hand face of the serration 28, referring to Fig. 1. After this face is trued, the slide 38 is indexed so as to bring the diamond point 35 30 into proper indexed relation to the next serration 29, and the grinding wheel is moved radially, as by turning the hand wheel 21, a very slight distance away from the truing device so that the serration 29 will be of 35 slightly greater diameter than the preceding one. The diamond point 35 will now be moved back and forth to true the right hand face of the serration 29. The diamond point is successively indexed to properly operate on the right hand faces of the succeeding serrations, the wheel, each time a new serration is to be trued, being moved a slightly greater distance away from the truing device. After the right hand faces 40 of all the serrations have been trued, the slide 38 is indexed so as to bring the diamond point 37 into proper relation to the left hand face of the serration 28 and after this face is trued, the diamond point is indexed so as to operate upon the left hand face of the second serration 29, the wheel 45 being first moved a slight distance away from the truing device. The diamond point 37 is then successively indexed so as to operate upon the left hand faces of the remaining serrations. All of the serrations 50 will now be of V shape and of increasing diameter. The side faces of the serrations are trued for a portion of their depths only 55 because the grooves in the grinding wheel are substantially deeper than the extent to which the serrations project into the work during the grinding operation.

60 The grinding wheel shown in Fig. 2 is trued in the same manner as that just de-

scribed in connection with the grinding wheel shown in Fig. 1, and, additionally, the edges of the serrations are truncated so as to form flats. These flats, in the present illustrative disclosure, are all of the same 70 width and are of progressively increasing diameter. To truncate the serrations or true the flats after the serrations have been truncated, the diamond point 36 is adjusted with respect to the serration 28^a and then the 75 slide 38 is moved longitudinally by means of the screw 39 so as to cause the diamond point to truncate the first serration 28^a. The diamond point is then moved slightly away from the grinding wheel and is moved across 80 the second serration 29^a, and this operation is repeated for the successive serrations.

85 It will be obvious that, since, during the grinding operation of the work, a plurality of serrations or cutting edges are simultaneously effective, and these serrations each perform but a relatively small part in grinding away excess metal from the work to bring the thread to the desired size and shape, the grinding of the work may be very 90 quickly carried out with precision, and the grinding wheel will not wear out so rapidly as would be the case where a single cutting serration were provided, so that repeated 95 truing of the wheel is not required, all of which means that threaded members, perfect in all respects, may be produced in a shorter space of time with less labor and at a materially reduced cost.

100 It will be seen that because of the fact that the serrations of the grinding wheel grind on only one face of any one of the thread convolutions at any one instant, the heating effect is considerably less than in the case where both sides of a thread are being 105 cut at the same time, so that the threads on the work will not be so highly heated that they will lose their temper or hardness. The grooves 27 provide plenty of room for a supply 110 of cooling fluid to immerse the work while grinding.

115 It will also be noted that because of the wide spacing of the serrations of the grinding wheel, and since the grooves in the grinding wheel may be substantially deeper than the extent to which the serrations project into the work during the grinding operation, there is ample room provided to insert the diamond point to true the wheel and it is necessary to true the side faces of the serrations for a portion of their depths only, all of which means that a much more precise and accurate form can be thus more conveniently obtained.

120 When it is desired to grind a thread of large lead angle, such as is shown in Fig. 6, the axis of the grinding wheel is inclined perpendicularly to the lead angle of the thread on the work. In this position, the serrations 55 of the wheel 56 extend substan- 125

tially in the direction of the thread angle of the work 58 instead of across the thread as would be the case if the two axes were placed parallel. In order to thus angularly 5 adjust the wheel so that its serrations are inclined correspondingly to the lead of the thread, the journal boxes 18 are adjustably mounted, by gibbs 60 (Figs. 1 and 8), on an arcuate bracket 61 arising from the slide 19. 10 The center of curvature of this bracket is preferably about a point 62 in the center of the grinding wheel, by which is meant a point at the axis of the wheel substantially midway between its ends. The serrations are 15 so shaped and trued that, at the point or line at which they engage the work, they will be of such contour and size as to properly and respectively operate on those portions or faces of the thread as has been 20 planned. Preferably, to true the grinding wheel to cut the thread to the proper dimensions, the truing device may be placed at the side of the wheel diametrically opposite the grinding point but this will depend on 25 conditions. In the present illustrative disclosure, the truing devices are moved in the plane including the axis of rotation of the work and the point 62. They move in a practical grinding plane which substantially 30 includes the axis of the work and the line of contact between the work and wheel so that the serrations on the grinding wheel are shaped and trued to desired size and shape. It is true that with the arrangement 35 of Figs. 6, 7 and 8, one end serration will engage the work slightly above the point of engagement between the central serration and the work, while the other end serration will engage the work slightly below the last 40 mentioned point, but for all practical purposes this deviation is negligible, and the practical grinding plane may be considered as substantially including the axis of the work and the point of contact between the 45 work and the several serrations or at least a mean of those points of contact. The diamond points shown in Figs. 1 and 7 are arranged to be moved in this plane. The truing of the wheel, while angularly disposed, is done in a manner similar to that 50 before described, so that the serrations are, for example, of progressively increasing size, for instance, in height, or all these serrations may be of the same size or cord 55 length in the grinding plane.

Thus, by the above construction and method, are accomplished, among others, the objects hereinbefore referred to.

As many changes could be made in the 60 above construction and method and many apparently widely different embodiments of this invention could be made without depart-

ing from the scope thereof, it is intended that all matter contained in the above description or shown in the accompanying drawing shall be interpreted as illustrative and not in a limiting sense. 65

It is also to be understood that the language used in the following claims is intended to cover all of the generic and specific 70 features of the invention herein described and all statements of the scope of the invention which, as a matter of language, might be said to fall therebetween. 75

I claim as my invention:

1. A wheel for grinding convoluted members comprising a wheel circular in cross section and provided with circumferential serrations on its periphery conforming generally in cross section to a screw thread, adjacent ones of said serrations being spaced a distance equal to a multiple of the distance between successive convolutions on the work thereby providing channels between the wheel and the work operated upon for the 85 passage of a cooling fluid. 80

2. A grinding device for grinding convoluted members comprising a grinding wheel of abrasive material provided with a plurality of circumferential serrations varying in size from one another and arranged to simultaneously grind a plurality of convolutions on the work and to successively grind increments from each of the convolutions. 90

3. A device for grinding convoluted members comprising a grinding wheel generally circular in cross section and provided on its periphery with a plurality of separate parallel serrations having sloping side faces 100 and of substantially the same shape and angle, said serrations being of progressively increasing diameter to cut successive increments from each convolution on the work. 105

4. A device for grinding convoluted members comprising a grinding wheel of abrasive material provided with separate parallel serrations having sloping sides and of the same cross sectional shape and angle in a plane to which the axis of the wheel is angularly disposed whereby said serrations in said plane will correspond in shape and angle to the grooves in the work operated upon. 110

5. A device for grinding convoluted members comprising a grinding wheel of abrasive material provided with a plurality of serrations corresponding in cross section to a screw thread, said serrations being of successively increasing chord length in a plane angularly disposed to the axis of the wheel and said serrations having sloping sides and being of the same sectional shape and angle in said plane. 115 120

BENGT M. W. HANSON.
